UNITED STATES PATENT OFFICE.

DAVID FRANKLIN SMITH, OF WASHINGTON, DISTRICT OF COLUMBIA.

COMPRESSOR.

Application filed August 27, 1927. Serial No. 215,971.

The invention relates to compressors for household refrigerator plants in which it is desirable to employ a compressor which will run for an extended period of time without requiring lubrication or other attention and which will be devoid of parts liable to work loose and drop out of place and cause jamming of the driving connections and rupture of the casing with the resultant danger to the 10 occupants of the house in which the compressor is installed.

In the drawings:

Figure 1 is a central vertical sectional view of the invention.

15 Fig. 2 is a vertical sectional view at right angles to Fig. 1.

Fig. 3 is a sectional view substantially in a plane cutting the main shaft and pinion shaft centers.

20 Fig. 4 is a side view of the main casing.

Fig. 5 is a sectional view on line 5—5 of Fig. 4.

Fig. 6 is a side view of one of the heads of the casing.

25 Fig. 7 is a sectional view on line 7—7 of Fig. 6.

Fig. 8 is an elevation of right side of Fig. 7.

30 Figs. 9, 10 and 11 are views of one of the heads of the casing.

In these drawings 1 indicates the main body of the casing in which the driving connection is housed, 2 the cylinder, of which there may be more than one, surmounting the 35 main body of the casing to which it is secured by flanges and bolts. The cylinder has a casing 3 at its upper end in which is housed the outlet valve 4, which is stressed by springs 5, 6. At 7 is an inlet port to

40 which the pipe for the ammonia is connected to supply the cylinder above the piston 8. The piston has a wrist pin 9 to which is connected the piston rod 10 extending from an eccentric strap 11 which surrounds the 45 eccentric 12 formed in one piece with the shaft 13 which is mounted in bearings 14, 15 of the heads 16, 16^a, which are secured to the main body of the casing by flanges and bolts. Between the eccentric and its strap

50 anti-friction means are located and in providing this means I have had in view the advantage to be derived from a construction from which no parts will become loose, drop out of place and lodge between the eccentric 55 strap and the casing where a jam may occur accompanied by rupture of the casing, escape

of the ammonia and danger to the householder.

In carrying out this part of the invention I employ anti-friction rollers 17, carried in 60 a cage made up of rings 18 between which the rollers are held and in which the journal pins of the rollers are mounted. This cage with the rollers mounted therein forms one complete body, to be handled as one unit. 65 This anti-friction body, together with the eccentric is slipped into the eccentric strap, their relative axial location being determined by a flange 11^a on the eccentric strap extending inwardly towards the axis of the 70 said strap. The eccentric has a flange or shoulder 12^a which confines the anti-friction means between itself and the flange 11^a. Each of these flanges are integral with the part which carries it so that there will be 75 no possibility of nuts, bolts, or screws becoming loose and drooping out because none are employed as a means for holding the flange to its carrying part, and the cage itself with the rollers will be held as one 80 body by the flanges against displacement. The anti-friction rollers bear upon a lining 11^b placed within the eccentric strap, and a lining 11^c surrounds the eccentric, fits against the flange of the eccentric at one end 85 and is confined by the flange of the strap at its other end.

The shaft 13 carries a gear 20 which is fixed thereon against a shoulder 21. The gear is driven by a pinion 23 mounted on a 90 shaft 24 arranged at the lower right hand portion of the main casing, said shaft extending through a stuffing box 24^b.

For lubricating the bearings of the main shaft 13 rings 25, 26 are provided depending 95 into compartments formed by walls 27 connected or formed with the heads 16, 16^a of the casing and to the hollow bearings 24^a of said heads in which the main shaft is journaled. These bearings are cut out intermediate of their length to receive the rings. 100

The bearing of the pinion shaft is lubricated by a ring 28 depending into a body of oil in a well 30 of the main casing. This ring is located in a cut out 29^a of the bearing 105 29 for the pinion shaft. This bearing 29 like the bearing 24^a is formed integral with the head of the casing.

It will be noticed that the main casing is formed with a circular flange 31, which is 110 eccentric relative to the main body of the casing, at the axial center of which latter

the shaft 13 is located. This flange in diameter, as seen in Fig. 4, includes within its scope, or the plane of its circuit, the main space 32 within the casing and also the space 33, Fig. 4, which is offset in relation to the main space and which is adapted to receive the bearing 29. By this construction the casing readily can be machined to receive the heads 16, 16^a and these heads can be of circular form, facilitating their machining to fit the casing body.

It will be noticed that each head carries its own bearing and its own lubricant well, the latter being formed by the partitions 34, which leave the open spaces at 35, so that oil splashing up from the main body of the casing will be caught by these partitions and held in the pockets.

I claim:

20 1. In combination in a compressor, a cylinder and piston, an eccentric drive for said piston, a shaft on which the eccentric drive is mounted, a casing enclosing said drive and having detachable heads having split bearings for said shaft, said heads having lubricant holding chambers, rings arranged in the split bearings and depending into the chambers, a pinion and gear connection for driving the shaft, a shaft carrying the pinion, a bearing for the said shaft integral with one of the heads, said bearing having a recess and a ring in said recess, and depending into the casing to lubricate the said bearing, substantially as described.

2. In combination, the casing, a removable head for each end of the casing, bearings on the heads, partitions on the heads forming oil pockets, an oil well in the main casing and a supplemental shaft bearing in one of the heads adjacent said oil well, substantially as described.

3. In combination, a shaft having an eccentric, a supplemental shaft, gearing between the said shafts, a casing having a main portion and an offset portion forming a well adjacent said supplemental shaft, a head having a bearing for the eccentric carrying shaft and a bearing for the main shaft, said casing and head having circular flanges eccentrically disposed relative to the main shaft and by which said head and casing are united, said circular flanges including within their planes the offset bearing for the supplemental shaft, substantially as described.

4. In combination, a casing, removable heads having bearings for a shaft and partitions extending from said bearings to the walls of the heads to brace said bearings and serving also as walls of oil pockets, substantially as described.

5. Apparatus according to claim 6 in which the partitions have spaces between their upper edges and the walls of the head so that oil splashing in the main body of the casing will be caught and held in said pockets, substantially as described.

In testimony whereof, I affix my signature.
DAVID FRANKLIN SMITH.
